SUPPORTING BRACKET

Emanuel J. Elson, Chicago, Ill.

Application October 14, 1933, Serial No. 693,542

2 Claims. (Cl. 248—207)

This invention relates to improvement in supporting brackets and refers specifically to a bracket structure for supporting boxes or other containers, shelves and the like, the structure being characterized in that the boxes, containers, shelves or the like may be supported at a plurality of predetermined angular positions by the use of one set of brackets.

The utility, objects and advantages of my invention will be apparent from the accompanying drawings and following detail description.

In the drawings, Fig. 1 is a side elevational view illustrating a pair of brackets comprising my invention supporting a box.

Fig. 2 is a top plan view of the brackets shown in Fig. 1.

Fig. 3 is a sectional view taken on line 3—3 of Fig. 1.

Fig. 4 is a sectional view taken on line 4—4 of Fig. 2.

Fig. 5 is a detailed top plan view, illustrating means for mounting the bracket upon a supporting clamp.

Fig. 6 is a view similar to that shown in Fig. 1 of another position in said brackets.

Fig. 7 is a similar view showing a further different position.

Fig. 8 is a similar view illustrating another position.

Fig. 9 is a similar view showing still another position.

Fig. 10 is a side elevational view illustrating my brackets as a shelf support.

Fig. 11 is a top plan view of the shelf and brackets.

Fig. 12 is a sectional view taken on line 12—12 of Fig. 11.

Fig. 13 is a sectional view taken on line 13—13 of Fig. 11.

Fig. 14 is a sectional view taken on line 14—14 of Fig. 11.

Referring in detail to the drawings, 1 indicates a supporting structure which may comprise a shelf, a counter or the like. Structure

1 as is usually the case, has a projecting ledge 2 upon which clamps 3 may be removably mounted.

Each clamp 3 may be constructed of metal and may comprise a pair of spaced projecting arms 4 and 5 rigidly secured at an angle to one

leg of U-shaped members 6. Arms 4 and 5 are adapted to brace the projecting ledge 2 and arm 5 may be tapped to receive the shank of set screw

7. When positioned upon ledge 2, arm 4 rests upon the top of said ledge and the end of set screw 7 may be brought into contact with the

lower face of the ledge whereby clamp 3 may be firmly maintained in position.

As will be hereinafter more fully described, the U-shaped portion 6 of each of the clamps 3 is adapted to support a bracket 8 which may be triangular in shape. For purposes of description, bracket 8 is shown in the form of an isosceles right triangle. However, it is to be understood that broadly my invention comprises a bracket of any geometric shape provided that the bracket when mounted on clamp 3 presents a straight side suitable for the support of a box container or shelf.

Bracket 8 is preferably constructed of metal and each leg thereof may carry a pair of opposite, rigidly attached or integral longitudinally disposed flanges 9 projecting from the face of the leg. The central portions 10 of each of the flanges 9 may be relatively higher than the remaining parts of the flanges for a purpose to be hereinafter set forth. A sleeve 11 may be provided adjacent corresponding ends of each of the legs of the bracket 8, said sleeve being soldered, welded or otherwise rigidly secured between opposite flanges 9 so as to provide a slot 15 in which one leg of the U-shaped member 6 may engage to support the bracket from the counter or shelf 1. The width and thickness of the leg of the U-shaped member 6 which thus engages in said slot are substantially the same 20 as the inner dimensions of the sleeve 11 so that said leg fits snugly in the slot obviating side play 25 of the bracket.

In utilizing brackets 8, a pair of clamps 3 may be secured to ledge 2 in spaced relation. 35 One position of the brackets is shown in Figs. 1 and 2 and to secure this position, that sleeve 11, hereinafter referred to as sleeve a, may engage the leg of U-shaped member 6. In this position the major portion of the brackets 8 is above 40 the plane of the ledge 2 and the box, container or shelf to be supported by the brackets may be disposed along the hypotenuse of the triangular brackets.

For purposes of description, brackets 8, in the 45 position shown in Figs. 1 and 2, are illustrated as supporting box 12. Box 12 may comprise a usual cookie or cake box, the body portion of which may be constructed of cardboard or the like. This type of box is well known in the art 50 and the upper side edges thereof are folded as shown best at 13 in Fig. 3 providing a downwardly extending flange 14. A cover 15 is utilized in conjunction with box 12 and may comprise a metal frame portion 16 and a hinged cover 17. 55

That portion of frame 16 which is positioned over the folded edges 13 of box 12, is provided with a downwardly extending flange 18, the lower end of which is curved as shown best at 19 in Fig. 3, 5 said curved portion being adapted to engage the lower edge of the downwardly extending flange 16 of box 12. Cover 17 may comprise a frame portion 20 having an aperture 21 in its center. Glass 22 may be positioned over said aperture 10 whereby the contents of box 12 may be observed by a prospective customer. By the provision of flanges 9 upon the hypotenuse legs of the brackets 8, box 12 may be supported between said brackets, the flanges being engageable between 15 flanges 16 and the side walls of the box. In this manner the plane of the box is disposed at an angle parallel to the hypotenuse of the brackets 8.

In the retail merchandising of such products 20 as food stuffs or the like, it is most desirable that the merchandise for sale be conspicuous. However, inasmuch as the shelf space, counter space, and show case space in the usual store is more or less limited, only a limited number of items 25 may be presented to the view of the customer. By the use of my invention the display facilities of a store may be materially increased inasmuch as a set of brackets 8 may be positioned as an auxiliary display support at substantially any 30 desired portion of the store. This means of providing display supports or facilities is extremely flexible inasmuch as the same can be conveniently changed from place to place depending upon variations in the stock distribution in the 35 store.

Referring particularly to Fig. 6, brackets 8 are shown as being mounted in a different position from those shown in Figs. 1 and 2. In this position of said brackets, member 6 engages sleeve 40 a oppositely to that shown in Figs. 1 and 2 whereby legs of the triangular brackets 8 are disposed parallel to the plane of the ledge 2. In this position of brackets 8, box 12 may be carried with its top in a horizontal position.

Fig. 7 illustrates another manner in which brackets 8 may be positioned. In this disposition of the brackets, member 6 engages that sleeve 11, hereinafter referred to as sleeve b, carried at one end of the hypotenuse. Box 12 supported by said brackets is positioned between the legs of the triangular members, the angle which the face of said box makes with the horizontal being slightly greater than that shown in Figs. 1 and 2. In like manner, member 6 may engage 55 sleeve b in the reverse direction whereby box 12 will be carried at the same angle as shown in Fig. 7, but will be positioned beneath the plane of the ledge 2. This latter disposition of the brackets is not shown but will be readily appreciated by those skilled in the art.

Referring particularly to Fig. 8 another position of brackets 8 is shown wherein member 6 engages that sleeve 11 carried upon one leg of the bracket adjacent the hypotenuse, said sleeve being hereinafter referred to as sleeve c. In this position of brackets 8, box 12 will be positioned upon the horizontal legs of the brackets, the face of the box being disposed at an angle to the horizontal the same as that shown in Figs. 1 and 2, 70 but said box will be positioned beneath the plane of ledge 2.

Fig. 9 illustrates another manner in which brackets 8 may be mounted wherein member 6 engages sleeve c in a direction opposite to that 75 shown in Fig. 8. In this position of the brackets,

box 12 will be disposed with its face in a horizontal plane, said plane being above the plane of ledge 2.

It can readily be seen that one set of brackets 8 may be utilized to support boxes or other containers in a plurality of angular positions permitting said boxes to be displayed in a conspicuous manner and in substantially a position which may be accommodated to the stock or fixture distribution of the store.

Referring particularly to Figs. 10, 11, 12, 13 and 14, an alternate use of my invention is shown. Brackets 8 may be mounted upon clamps 3 in any one of the positions shown in Figs. 1, 6, 7, 8 or 9, or said brackets may be mounted as 15 shown in Fig. 10. A shelf 23 may be supported by brackets 8 and may comprise members 24 and 25, each of which includes a flat plate portion, one longitudinal edge of which is bent at an angle to the plane of the plate as shown best at 20 26 in Figs. 10 and 12. Members 24 and 25 may be telescopically related with respect to each other, member 25 having folded edges 27 and 28 within which member 24 may slide to increase or decrease the effective length of shelf 23. Each 25 member 24 and 25 may be provided with transverse spaced slots 29 into which the extended central portions 10 of flanges 9 may be positioned whereby members 24 and 25 comprising shelf 23 may be supported. When shelf 23 is carried 30 at an angle as shown in Fig. 10, or in a position corresponding to the disposition of the brackets in Figs. 1, 7 or 8, the bent portions 26 are positioned at the lower edge of said shelf, whereby articles of merchandise may be supported and 35 prevented from sliding from the shelf. By the engagement of flanges 10 and slots 29, shelf 23 when thus disposed, is prevented from sliding from the supporting brackets. In this connection, the ends of flanges 10 may be provided with 40 slots 30 whereby members 24 and 25 may be more positively secured to the brackets.

By the provision of the telescopic arrangement of members 24 and 25, shelf 23 may be increased or decreased in length, within predetermined limits, by changing the distance between brackets 8. In the event that a maximum shelf length or spread is desired, the inner slots 29 of the members 24 and 25 may be brought into coincidence and a bracket 8 may be utilized to support the central portion of the shelf, flanges 10 of the central bracket engaging in the registered slots 29. In a similar manner more sections of shelf may be added, said sections being similar to members 24 and 25, or if the members 24 or 55 25 are constructed of relatively great length or are employed to support comparatively heavy weights, slots, not shown, similar to slots 29 may be provided intermediate the lengths of said members, whereby additional brackets 8 may be 60 used.

It is apparent that herein is provided a bracket structure which is ideally adapted to display purposes, the bracket being especially characterized in its flexibility of use, economy of construction 65 and simplicity of design. As has been hereinbefore described, boxes, containers or shelves may be supported at any one of a plurality of angular positions and the change from one position to another involves a minimum number of simple 70 operations. The brackets may be supported from any type of ledge, shelf or counter and if desired, the "bite" of clamps 3 comprising arms 4 and 5 and screw 7, may be so arranged as to grip a vertical or other angularly projecting ledge. In 75

this manner, brackets 8 may be supported from bins or the like, not shown.

I claim as my invention:

1. A supporting bracket of the class described having a plurality of sides and being polygonal in shape, each side of said polygon being provided with a slot adjacent an end of said side, one of which slots is engageable with a tongue for carrying said bracket.

2. A supporting bracket of the class described having a plurality of sides and being polygonal in shape, at least two sides of said polygon being of different length, each side of said polygon being provided with a slot adjacent an end of said side, one of which slots is engageable with a tongue for carrying said bracket. 5

EMANUEL J. ELSON.
